UNITED STATES PATENT OFFICE.

CHARLES E. NETHERTON AND JOHN W. NETHERTON, OF NORTH JUDSON, INDIANA.

SMOKE-CONSUMER.

Specification of Letters Patent. Patented Nov. 30, 1915.

1,162,093.

Application filed March 20, 1915. Serial No. 15,917.

To all whom it may concern:

Be it known that we, CHARLES E. NETHERTON and JOHN W. NETHERTON, citizens of the United States, residing at North Judson, in the county of Starke and State of Indiana, have invented certain new and useful Improvements in Smoke-Consumers, of which the following is a specification, reference being had to the accompanying drawings.

This invention relates to smoke consumers, and has for its primary object to provide a smoke consuming apparatus which is particularly applicable to the furnaces of locomotive boilers for the purpose of consuming the products of combustion.

The invention has for a more particular object to provide a smoke consumer embodying pipes connected to the smoke stack at one of their ends and opening at their other ends into the fire box of the furnace, means for creating a forced draft through said pipes, and additional means for injecting steam into the pipes whereby the consumption of the smoke and gases is assured.

Our invention has for another important object to provide improved means for controlling the admission of the products of combustion into the conducting pipes, said pipes having an air draft flue connecting therewith, intermediate of their ends, a valve for controlling the admission of air to the pipes, and steam injecting pipes connected to the locomotive boiler and extending downwardly through the air draft and into the respective smoke conducting pipes.

The invention has for a further general object to improve and simplify the construction of smoke consuming apparatus of the above character, whereby the same may be readily applied to the ordinary locomotive furnace, and is highly efficient and reliable for the purposes in view.

With the above and other objects in view, our invention consists in the novel features of construction, combination, and arrangement of parts to be hereinafter more fully described, claimed, and illustrated in the accompanying drawings, in which,

Figure 1 is a vertical section of a locomotive boiler having our invention applied thereto; Fig. 2 is a top plan view; Fig. 3 is a section taken on the line 3-3 of Fig. 1; and Fig. 4 is a section taken on the line 4-4 of Fig. 1.

Referring in detail to the drawings, 5

designates the trunk or body of the locomotive boiler, in the heads of which the ends of the usual fire tubes 6 are secured.

7 designates the fire box located at the rear end of the boiler and 8 the smoke receiving chamber at the forward end thereof, beyond the fire tubes 6. With this chamber, the smoke stack 9 communicates.

Parallel longitudinally disposed pipes 10 extend over the top of the boiler and are convergently disposed at their forward ends and connected to each other. These connected ends of the pipes are in communication with the smoke stack 9. The rear ends 70 of the pipes 10, extending through the cab of the locomotive, are downwardly turned and disposed through the rear wall of the fire box at opposite sides of the feed door, as shown at 11.

75 A damper plate 12 is pivotally mounted at one of its ends upon the upper edge of the rear wall of the smoke stack 9, the pivot rod 13 of said damper plate being provided upon one end with a crank arm 14 to which a longitudinally disposed rod 15 is pivotally connected at one of its ends. This rod extends into the cab of the locomotive and is connected to a lever 16 pivotally mounted upon a rack 17, said lever carrying the usual spring pressed locking dog 18 for engagement with the teeth of the rack. By shifting the rod 15 in one direction, the damper plate 12 may be obliquely disposed with its lower free edge in contact with the front 80 wall of the smoke stack 9 so that said damper plate will serve as a deflecting means for the smoke and products of combustion entering the smoke stack, and direct the same into the pipes 10. It will be understood that the pipes 10 may be cylindrical or of any other desired form.

85 19 designates an air draft flue which is located intermediate of the ends of the pipes 10 and slightly in advance of the locomotive cab, said draft flue having branches 20 communicating with the respective pipes. Upon the upper rear edge of this draft flue, the damper or flue plate 21 is pivotally mounted, the pivot thereof having a crank arm 22 90 to which the operating rod 23 is connected. This rod may be held in adjusted position in a similar manner to the rod 15, as above explained, and it will be understood that, upon the proper manipulation thereof, the plate 21 may be raised to open the upper 95 end of the draft flue and permit the entrance 100 105 110 115

of air thereto. This plate, being inclined forwardly when in its open position, acts to direct a strong current of air downwardly through the flue and into the smoke conducting pipes, whereby the smoke is forcibly driven through said pipes into the rear ends thereof, and eventually into the fire box of the locomotive. In order to further facilitate this movement of the smoke, we provide 10 the steam pipe 24 which is connected to the steam space of the locomotive boiler and is extended through the rear wall of the draft flue. Inferiorly of the draft flue, said steam pipe is provided with the branches 25 which 15 project into the respective smoke conducting pipes 10 and have their extremities rearwardly turned or curved. A suitable valve 26 is located in the pipe 24 whereby the supply of steam to the pipes 10 may be controlled and regulated. By opening this valve, it will be understood that jets of steam under high pressure are delivered into the respective pipes 10 so as to drive the smoke rearwardly through said pipes and into the 25 fire box.

From the foregoing description, it is believed that the construction, manner of operation and several advantages of our invention will be clearly and fully understood. 30 The smoke and products of combustion entering the forward ends of the smoke pipes, is carried by the air draft and steam which is admitted to said pipes and forcibly delivered into the fire box over the fuel bed, 35 whereby it is consumed. It will be understood that the damper plate 12 is only disposed in its fully closed position when the fire box is fed with fresh fuel, and said plate is opened at intervals to permit the uncon- 40 sumed products of combustion to pass off through the stack 9 to the atmosphere. By dampening the gas and smoke, its combustion upon delivery to the fire box is assured. By the provision of such a smoke consumer, 45 the emission of smoke and sparks from the stack of the locomotive is greatly lessened and danger of conflagrations, due to live cinders falling along the track, is overcome. Our invention is comparatively simple in 50 its construction, and may be readily applied to locomotive boiler furnaces at present in common use.

While we have shown and described the preferred construction and arrangement of 55 the several elements employed, it is to be

understood that the apparatus is susceptible of considerable modification therein, and we, therefore, reserve the privilege of resorting to all such legitimate changes as may be fairly embodied within the spirit and scope of the invention as claimed.

Having thus fully described our invention, what we desire to claim and secure by Letters Patent is:—

1. The combination with a locomotive 65 boiler furnace having a smoke collecting chamber at one end provided with a stack and a fire box at its other end, of a damper plate mounted in said stack, spaced longitudinally extending smoke conducting pipes 70 connected to the stack at one of their ends and having their other ends opening into the fire box, a damper plate arranged in said stack, means for positioning said damper plate to direct the products of combustion 75 into said pipes, an air flue communicating with said pipes intermediate of their ends, a damper plate mounted upon said flue, and means for positioning said damper plate to forcibly direct a draft of air downwardly 80 through the flue and into said pipe.

2. The combination with a locomotive boiler furnace having a smoke collecting chamber provided with a stack and a fire box, of spaced longitudinally extending 85 pipes connected at one of their ends to said stack and having their other ends opening into the fire box, a damper plate mounted within the stack, means for positioning said damper plate to direct the products of combustion into said pipes, an air flue communicating 90 with said pipes intermediate of their ends, a plate pivotally mounted upon said flue, means for positioning said plate to forcibly direct an air draft downwardly 95 through the flue and into said pipes, a steam supply pipe connected to the boiler and extending into said flue, and branch pipes extending from the steam supply pipe into the respective smoke conducting pipes and 100 having their extremities extended longitudinally into said pipes.

In testimony whereof we hereunto affix our signatures in the presence of two witnesses.

CHARLES E. NETHERTON.
JOHN W. NETHERTON.
